SAFETY RAZOR

John D. Karle, Roselle Park, N. J.

Application March 21, 1932, Serial No. 600,147

17 Claims. (Cl. 30—47)

This invention relates to improvements in safety-razors and has for its primary object to provide improved means for compactly assembling as a unit the several members of a safety-razor 5 for greater convenience of transportation and storage.

A further object of the invention is to retain in the improved safety-razor the characteristic blade-clamping features, the general appearance 10 and the sanitary advantages of the commercially well known and approved Gillette type of safety-razor.

Other and more specific objects of the invention will be apparent from the following 15 description and claims.

To the attainment of the objects of the invention, the present improvement in its preferred embodiment comprehends the employment of a detachable connection-element between the 20 razor-head and handle, serving for clamping the blade in the razor-head in the usual manner and for securing the handle to the razor-head in angularly different positions of the handle.

In the accompanying drawing, Fig. 1 is a side 25 view, partly in section, of a safety-razor including a preferred form of key-nut connection between the razor-head and handle, in the operative position of the latter. Fig. 2 is a longitudinal section of the handle of the razor shown in Fig. 1. Fig. 3 is a perspective view of the preferred key-nut. Fig. 4 is a sectional view of the razor-head, with the handle shown in full lines secured to the 30 razor-head at a right-angle to the operative position thereof illustrated in dotted lines. Figs. 5 and 6 are views illustrating a modified arrangement according to which the key-nut is provided with a lock-pin and the handle is correspondingly slotted. Fig. 7 is a sectional view of the key-nut and partly of the handle illustrating a further modification according to which the key-nut and handle are correspondingly squared. Fig. 8 is a section substantially on the line 8—8 of Fig. 7. Fig. 9 is an end view of the key-nut as viewed from the right in Fig. 7. Figs. 10 and 11 are perspective views illustrating still further modifications according to which the head of the key-nut is slotted and the end of the handle is correspondingly recessed. Fig. 12 is a side view of a collapsible handle provided with a key-nut arrangement as illustrated in Fig. 1 of the drawing. Fig. 13 is a longitudinal section of the handle illustrated in Fig. 12.

Referring to the drawing, the present invention is illustrated as embodied in a Gillette 55 safety-razor having the usual separable elements including a handle 1 and a razor-head comprising a segmental blade-clamping member 2, a blade 3 and a combination blade-clamping and guard-member 4. The clamping-member 2 has 60 the usual threaded stud 5 projecting integrally

therefrom, said stud in the assembled condition of the razor-head elements extending through suitable apertures in the blade and the guard-member.

In the commercial type of razor before referred to, the handle is adapted to be threaded upon the stud 5, the end of the handle engaging the guard-member 4 to thereby securely clamp the several razor-head elements in operative relationship. Conversely, when the handle is unthreaded from the stud 5, the several elements of the razor are free to be separated. It is preferred to retain this simple and characteristic feature of Gillette safety-razors in the present improvement, with additional features providing 15 for readily detaching the handle from the razor-head in the clamped condition of the razor-head elements and for thereafter re-attaching said handle to the razor-head in a more compact disposition of the handle better adapted for transportation and storage of the outfit as an assembled unit.

For this purpose, there is substituted for the usual threaded end of the handle a detachable connection-element, herein termed a key-nut 6, 25 preferably having at one end an external flange or head 7, and provided longitudinally thereof with a threaded aperture 8 for receiving the stud 5. In the construction illustrated in Figs. 1 to 4 of the drawing, the key-nut 6 is of cylindrical 30 form and has a substantially diametrical slot 9 in its end opposite to the flanged end thereof, said key-nut being preferably hardened and tempered whereby the slotted ends thereof have resilient characteristics.

As herein illustrated, the handle 1 is made into cylindrical form of drawn sheet metal which may be suitably knurled, one end of the handle having a peripherally knurled cap 10. The opposite end of the handle is reduced in size to provide a bore 40 closely embracing the key-nut 6, said reduced end of the handle being provided with a key-pin 11 intersecting said handle bore and adapted to enter the key-nut slot 9. Substantially midway between its ends the handle 1 is provided with a bushing 12 apertured transversely of the length 45 of the handle to provide a bore corresponding to the bore of the reduced end of the handle 1, i. e., to fit closely upon the key-nut 6.

The simplicity of the described arrangement 50 lends itself to a ready comprehension of its functions and efficacy. The razor-head parts may be initially assembled for shaving as heretofore. The key-nut 6 is thereupon threaded upon the stud 5 and the handle 1 is endwise frictionally 55 fitted upon the key-nut with the pin 11 entering the slot 9. By now rotating the handle about its longitudinal axis, the nut 6 is also rotated by reason of the pin 11 connection therewith, whereby said nut may be brought into engagement with 60

the guard-member 4 to securely clamp the razor-head members. The spaced segments of the slotted key-nut are preferably slightly spread to frictionally hold the handle 1 in its operative position with the required security for shaving purposes. The described slip-joint connection between the handle and the razor-head permits withdrawal of said handle endwise from the key-nut 6, whereupon the handle may be applied sideways upon said key-nut by frictionally fitting the handle-bushing 12 thereupon, as illustrated in full lines in Fig. 4 of the drawing. It will be noted that the handle is now compactly disposed substantially parallel with the length of the 15 razor-head, with all of the razor-head parts secured against inadvertent separation while changing the position of the handle, thus providing for conveniently storing or transporting the razor and for subsequently using the razor 20 without any time-wasting effort to search for and reassemble all of the individual parts thereof. It will be understood, of course, that when the handle 1 is operatively applied to the razor-head, as illustrated in Fig. 1, it may be rotated in a 25 direction to unclamp and entirely separate the razor-head parts with the key-nut frictionally retained by the handle after detaching the handle from the razor-head. In other words, the handle 1 and key-nut 6 may be left associated 30 as a handle unit and employed precisely as is the handle of the prior commercially used outfit, so that the user of the improved razor need not in any way change his shaving habits.

It is obvious, of course, that various modifications of the above specifically described construction may be made all within the spirit and scope of the invention. For instance, in a modification as illustrated in Figs. 5 and 6 of the drawing, there is provided a key-nut 13 of cylindrical form having a flanged head 14 and a threaded aperture 15 to receive the clamping-member stud 5, as before. However, in this modification it is the key-nut 13 which carries a key-pin 16 having its ends projecting from diametrically opposite sides of the key-nut to enter slots 17 in the handle 18. In this form of construction, the slotted handle affords the requisite frictional grip upon the key-nut so that the latter need not be slotted for this purpose.

Obviously, the key-nut 13 might be otherwise provided with a projecting nub or nubs to function in the same manner, or the pin may be so arranged that only one end thereof projects from the key-stud. The handle 18 is provided intermediate the ends thereof with a bushing 19 disposed transversely of the length of the handle, said bushing having diametrically opposed and parallel grooves 20 in its inner face to receive the 60 projecting ends of the key-nut pin 16 when the handle is applied sidewise upon said key-nut.

A further modification is illustrated in Figs. 7, 8 and 9 of the drawing, according to which a key-nut 21 has a squared shank 22 of which the 65 edges are preferably rounded. The mating end of a handle 23 is correspondingly squared to obtain the desired nut-rotating key effect. In this form of construction it is preferred to provide the requisite frictional engagement between the handle and nut by splitting the nut, as illustrated, and slightly spreading the segments thus formed.

The handle 23 may be provided with a cylindrical bushing 24 as in Fig. 1, which bushing may 75 be readily fitted upon the squared shank 22 of

the key-nut by reason of the rounded edges thereof.

In a still further modification, the flanged end 25 of a key-nut 26 is slabbed to provide opposed key-faces 27 adapted to be engaged by parallel walls 28 formed in a tubular handle 29 by suitably notching the reduced end thereof.

In Figs. 12 and 13 of the drawing, there is illustrated a telescopically collapsible handle provided with the key-nut arrangement of Fig. 1, although any other selected form of key-nut device may be employed therewith. In this construction, a tubular outer handle-member 30 telescopically receives an inner handle-member 31 provided with one or more longitudinal slots 32 to form resilient segments adapted to frictionally engage the outer member 30 for the purpose of retaining any extended or collapsed relationship of said members. Fixed in the inner handle member is a diametrically disposed bushing 33 15 projecting slightly beyond the outer face of the inner handle-member to slidably enter parallel slots 34, formed in the outer handle-member and terminating within the ends thereof. The ends of the slots 34 thereby serve to limit the relative 20 endwise movement of the handle-members and the bushing 33 secures said members against relative rotation. When the collapsible handle is detached endwise from the key-nut it may be 25 sidewise applied thereto by sliding the bushing 33 upon the key-nut 6 in the same manner as illustrated in full lines in Fig. 4 of the drawing, with the handle-members collapsed so as to be of substantially the same length as the razor-head, whereby the razor parts occupy a minimum of 30 space and are nevertheless combined for convenient handling as an assembled unit.

Having thus set forth the nature of the invention, what I claim herein is:

1. A safety-razor comprising separable blade-clamping members, means for bringing said members into blade clamping relationship including a connection-element threaded upon one of said members, a handle having in one end thereof a bore adapted to slidably receive said connection-element endwise of the handle, said handle being provided intermediate its ends with a bore transverse to the end bore of the handle adapted to slidably receive said connection-element side- 40 wise of the handle, and means for detachably retaining said handle upon said connection-element in either position of the handle thereupon.

2. A safety-razor comprising separable blade-clamping members, a threaded stud projecting from one of said members, a connection-element 45 threaded upon said stud to effect blade-clamping relationship of said members, and a handle provided with bores disposed transversely of each other to slidably receive said connection-element in relatively transverse positions of said handle.

3. A safety-razor comprising separable blade-clamping members, means for bringing said members into blade clamping relationship including a longitudinally slotted connection-element 50 threaded upon one of said members into engagement with the other member, and a handle provided with bores disposed transversely of each other, said bores being of suitable diameter to frictionally receive the slotted end of said connection-element in relatively transverse positions of 55 said handle.

4. A safety-razor comprising separable blade-clamping members, means for effecting blade-clamping relationship of said members including a threaded stud projecting from one of said 60

members, a connection-element threaded upon said stud having resilient handle-engaging means, and a handle provided with bores disposed transversely of each other adapted to frictionally receive said connection-element in relatively transverse positions of said handle.

5. A safety-razor comprising separable blade-clamping members, means for securing said members in blade-clamping relationship including a threaded stud projecting from one of said members, a slotted connection-element threaded upon said stud, and a handle detachably fitted upon said connection-element having keying means coacting with the slot of said connection-element to secure the latter against rotation relatively to said handle.

6. A safety-razor comprising separable blade-clamping members, means for securing said members in blade-clamping relationship including a threaded stud projecting from one of said members, a slotted connection-element threaded upon said stud, and a handle having in one end thereof a bore adapted to detachably receive said connection-element, a key-pin intersecting said handle bore in position to enter the slot of said connection-element, said handle having a bore intermediate its ends to receive said connection-element in an inoperative position of the handle.

7. A safety-razor comprising separable blade-clamping members, means for securing said members in blade-clamping relationship including a threaded stud projecting from one of said members, a connection-element threaded upon said stud having a key-pin projecting peripheral-ly therefrom, and a handle having a bore adapted to detachably receive said connection-element, said handle having means coacting with said key-pin to restrain said connection-element against rotation relatively to said handle.

40 8. A safety-razor comprising separable blade-clamping members, means for securing said members in blade-clamping relationship including a threaded stud projecting from one of said members, a connection-element threaded upon said stud having opposed key-faces, and a handle having in one end thereof a bore adapted to detachably receive said connection-element, said handle bore being notched to provide opposed walls adapted to engage the key-faces of the 45 connection-element to thereby restrain the latter against rotation relatively of the handle.

9. A safety-razor comprising separable blade-clamping members, means for securing said members in blade-clamping relationship including a threaded stud projecting from one of said members, a connection-element threaded upon said stud provided with a plurality of substantially flat key-faces, and a handle having in one end thereof a bore conforming in configuration 50 with the key-faces of the connection-element and in size to slidably receive said connection element.

10. A safety-razor comprising separable blade-clamping members, means for securing said members in blade-clamping relationship including a threaded stud projecting from one of said members, a connection-element threaded upon said stud, a tubular handle having an open end adapted to detachably receive said connection-element 55 in an operative position of the handle, said handle being provided intermediate its ends with a bushing apertured transversely of the length of the handle to detachably receive said connection-element in an inoperative position of the handle.

11. A safety-razor handle provided in one end thereof with a bore, and having a connection-element threaded for attachment to a razor-head, said connection-element being detachably keyed to said handle within said bore for rotation in opposite directions of said connection-element with said handle.

5 12. A safety-razor handle provided at one end with a razor-head connection-element detachably keyed to the handle for rotation therewith, said handle having intermediate its ends a bore adapted to slidably receive said connection-element.

13. A safety-razor comprising separable blade-clamping members, a threaded stud projecting from one of said members, a connection-element threaded upon said stud, a handle frictionally disposed in an operative position upon said connection-element to extend in a direction substantially normal to said blade-clamping members 20 and for endwise sliding detachment from said connection-element, and keying means compelling unison rotation of said connection-element with the handle in said operative position thereof.

25 14. A safety-razor comprising separable blade-clamping members, means for effecting blade-clamping relationship of said members including a threaded stud projecting from one of said members, a connection-element threaded upon said stud, a handle having one end thereof frictionally disposed upon said connection-element for sliding detachment of the handle endwise from the connection-element in a clamping-member securing position upon said stud of the connection-element, and keying means compelling rotation of said connection-element with said handle upon rotation of the handle about its longitudinal axis.

30 15. In combination, a razor handle, said handle having a stem formed with a diametral opening therein, a blade-clamping member, a blade, and a guard-plate, said clamping member having a stud adapted to project into said opening in said stem and having resilient means at its extremity for frictionally engaging the walls of 35 said opening thereby frictionally to hold said guard-plate, blade, and clamping member upon said stem.

40 16. A safety-razor comprising separable blade-clamping members, a threaded stud projecting from one of said members to effect blade-clamping relationship of said members, a connection-element carried by said stud, and a handle provided with bores disposed transversely of each other to slidably receive said connection-element 45 in relatively transverse positions of said handle.

55 17. In a collapsible safety-razor structure, the combination of a tubular housing having one open end with a closure plug adapted to be secured in said open end, said closure plug forming part of a handle extending into said tubular housing, said handle having a transversely extending bore, a razor head assembly having a shank for attachment to said handle, said shank extending into said transversely extending bore 60 with the major axis of the head assembly extending longitudinally of the handle, and a connection element for gripping said shank and holding the parts in the last mentioned position, said connection element comprising a spring collar 65 arranged in said transverse bore and having an inwardly extending resilient finger for engaging said shank.

70 JOHN D. KARLE.
